UNITED STATES PATENT OFFICE.

JAMES E. SIMPSON, OF BROOKLYN, NEW YORK.

TYPE-WRITING MACHINE.

1,317,180.

Specification of Letters Patent. Patented Sept. 30, 1919.

Application filed January 4, 1919. Serial No. 269,623.

To all whom it may concern:

Be it known that I, JAMES E. SIMPSON, a citizen of the United States, and resident of the borough of Brooklyn, in the county of 5 Kings and State of New York, have invented certain new and useful Improvements in Type-Writing Machines, of which the following is a specification.

This invention relates to inking and 10 inking means for the ribbons employed with typewriting and like machines, and my present improvements have particular reference to an easily attachable and detachable device, which can be applied quickly and conveniently 15 to a machine by the user thereof, without requiring the services of a skilled mechanic for its application.

Further my improvements contemplate the provision of controlling means for the inking 20 device whereby the same is actuated intermittently through the operation of the type bars, which in their printing strokes move an inking pad into contact with the ribbon to impart ink to the latter while said 25 ribbon is moving under the influence of the ribbon feed mechanism; and, a still further feature of improvement consists in means for moving the inking pad into and out of its operative relation with the ribbon.

30 In the drawings:—

Figure 1 is a front elevation of a portion of a type-writing machine to which my improvement is attached, and

Fig. 2 is a top plan view of the same.

35 In the figures only such portions of a type-writing machine are shown as will serve to explain the relation of my inking device therewith. Thus let 1 indicate a platen, 2 the guide jaws for centering the types on 40 the type bars to the printing position, 3 a type bar bearing a type 4 and 5 a ribbon spool casing mounted on bracket 6 and having the pivot 7 to carry a ribbon spool (not shown).

45 The inking device has a base plate 9, provided at one end with lugs 10, to fit over the vertical wall of casing 5, for support, and said plate 9 is shaped at its other end, as 11, to fit against the under surface of a 50 guide jaw 2; while a loose piece 12, held to plate 9 by a thumb screw 13, is adapted to be clamped down tightly upon the upper surface of jaw 2 to bind the latter securely between said piece 12 and plate 9. In this 55 manner the device may be removably attached to a typewriting machine.

While the attaching means shown are such as particularly suit an Underwood machine, they may obviously be modified, while of the same general character, to serve for other 60 makes of typewriting machines.

Mounted on the base 9 by pivot 14, is an arm 15, which carries a pin 16 that serves as a pivotal bearing for an inking pad or roller 17, a cap 18 being screwed upon the 65 pin 16 to hold the inking roller in place. The arm 15 is held outwardly against a stop 19 by a spring 20, that presses from the opposite side of said arm against a projection 21 thereon. The arm 15 is so positioned that 70 its free end lies in the path of the types as they are carried by the type arms toward the printing point, thereby in the successive strokes of the type bars setting up a vibratory action for the inking pad.

75 The ink ribbon 22, which is supported in the usual manner over the printing point of the platen, is passed around a pin 23 and thence over the surface of a roller 24 in its path of travel to the ribbon spool 25. Said 80 roller 24 is eccentrically mounted by a bushing 26 on a pivot 27, a lever 28 engaging with said bushing to rock said roller, whose range of movement is limited by the lever 28 engaging in opposite directions, with the pin 85 23 and a pin 29. The pad 17 and roller 24 are so relatively located that, with the pad 17 in its normal position and the roller 24 rocked until its lever 28 is engaged with the pin 23, then the pad 17 on its vibratory 90 movement will make intermittent contact with the ribbon passing around said roller 24; but when the roller 24 has been rocked in the opposite direction, so that the lever 28 is brought into contact with pin 29, then the roller 24 has thereby been spaced apart 95 from pad 17 beyond the zone of vibratory activity of said pad, so that the ribbon then feeds over roller 24 without receiving further accessions of ink from pad 17.

100 It will be understood from the foregoing description of parts and their operative and inoperative relations, that the inking pad will be brought into intermittent contact with the ribbon in the feed movement of the latter, through the operation of the types, when the roller 24 is rocked in one position. Also, that when said roller is rocked into the other position, then the inking operation 105 will be suspended. I have found it desirable to discontinue the inking operation 110 when a worn ribbon has been revivified, to

avoid imparting an excess of ink to the ribbon, until said ribbon again needs a further supply of ink. By simply moving the lever 28 in one or the other direction the ink supply is put into or out of service.

It will also be understood that my improvement is equally applicable for the purposes of re-inking a used ribbon or for supplying ink to a plain ribbon.

10 Or the pad may merely carry moisture to brighten up a dry ink ribbon.

Variations may be resorted to within the spirit and scope of my said invention and parts thereof used without others.

15 I claim:—

1. The combination, with a typewriting machine having type bars and an inking ribbon, of revivifying means for said ribbon, and means located in the path of said 20 type bars to be actuated thereby for intermittently applying said revivifying means with the operation of said type bars.

2. The combination, with a typewriting machine having type bars and an inking ribbon, of revivifying means for said ribbon, means located in the path of said type bars to be actuated thereby for intermittently applying said revivifying means with the operation of said type bars, and means for rendering said revivifying 30 means inactive.

3. The combination, with a typewriting machine having type bars and an inking ribbon, of a device removably attachable to said machine and comprising means for revivify-

ing said ribbon, and means located in the 35 path of said type bars to be actuated thereby for intermittently applying said revivifying means with the operation of said type bars.

4. The combination, with a typewriting 40 machine having type bars and an inking ribbon, of a device removably attachable to said machine and comprising means for revivifying said ribbon, means located in the path of said type bars to be actuated thereby for 45 intermittently applying said revivifying means with the operation of said type bars, and means for rendering said revivifying means inactive.

5. The combination, with a typewriting 50 machine, having an inking ribbon, of a member removably attachable to said machine, an inking pad, a vibratory arm mounted on said member, said arm carrying said pad, and said arm located in the path of the type bars 55 to be intermittently actuated thereby, a return spring for said arm, a guide roller for said ribbon, and means for moving said roller into and out of the zone of vibratory activity of said pad.

Signed at Brooklyn, in the county of Kings and State of New York, this 20th day of December, A. D. 1918.

JAMES E. SIMPSON.
